UNITED STATES PATENT OFFICE.

CONYERS BUTTON, OF PHILADELPHIA, PENNSYLVANIA.

DESIGN FOR STOCKING-FABRIC.

Specification forming part of Design No. 5,099, dated July 11, 1871.

To all whom it may concern:

Be it known that I, CONYERS RUTTON, of Philadelphia, county of Philadelphia, State of Pennsylvania, have invented or produced a Design for a Stocking-Fabric, of which the following is a specification:

The figure in the accompanying drawings represents sufficient of a stocking-fabric to illustrate my design, which consists mainly of stripes A A, alternated with narrow ribs B, each of the said stripes A being composed of three narrow bars, arranged as shown.

Irrespective of the colors employed, I claim—
The design for a stocking-fabric, substantially as described, and as represented in and by the accompanying drawing.

In testimony whereof I have signed my name to this specification in the presence of two subscribing witnesses.

CONYERS BUTTON.

Witnesses:
